UNITED STATES PATENT OFFICE.

FERDINAND MEYROSE, OF ST. LOUIS, MISSOURI.

LANTERN.

SPECIFICATION forming part of Letters Patent No. 363,161, dated May 17, 1887.

Application filed December 6, 1886. Serial No. 220,823. (No model.)

To all whom it may concern:

Be it known that I, FERDINAND MEYROSE, of the city of St. Louis, in the State of Missouri, have invented a certain new and useful 5 Improvement in Lanterns, of which the following is a full, clear, and exact description, reference being had to the accompanying drawings, forming part of this specification, and in which—

10 Figure I is a side elevation of a lantern embodying my invention, the globe being shown in its lower or using position. Fig. II is a similar view with the globe raised. Fig. III is an enlarged vertical section of the guide-tube taken on line III III, Fig. I, showing the cap in its lower position. Fig. IV is a similar view taken on line IV IV, Fig. II, showing the cap raised. Fig. V is an enlarged transverse section taken on line V V, 15 Fig. I. Fig. VI is a vertical section taken on line VI VI, Fig. V. Fig. VII is an enlarged detail view showing part of the disk and one of the fasteners. Fig. VIII is an enlarged transverse section taken on line VIII VIII, 20 Fig. I. Fig. I.

25 My invention relates to certain improvements in lanterns; and it consists in features of novelty hereinafter fully described, and pointed out in the claims.

30 Referring to the drawings, 1 represents the reservoir or fount; 2, the usual air-tubes; 3, the burner; 4, the disk in which the globe fits; 5, the globe; 6, the cap connected to the upper end of the globe by wires 7; 8, the guide-tube of the cap, and 9 the handle. These 35 parts in themselves may all be made of any well-known form or construction.

The globe and disk are connected together by a cheap and novel fastening consisting of 40 two or more wires, 10, that are inserted in holes of the disk and bent, as shown in Figs. V and VI, so that their ends 11 will come against the globe and hold it on the disk. The lower ends, 12, of these fasteners are preferably formed with loops to provide a finger-hold by which the fasteners are turned from the position shown on the left-hand side of Fig. V to the position shown on the right-hand side, (the latter position being that also shown 45 in Fig. 6,) and vice versa, when the globe and disk are to be connected and disconnected.

This device forms a cheap and effective means of securing the disk and globe together, so that when the latter is raised to expose the burner the former will be lifted with it. 55

Secured to and extending upward from the cap 6 are two segment-plates, 13, that conform to the circular guide-tube 8, as shown in Fig. VIII. They extend from the cap to a point above the guide-tube, and are preferably 60 united at top by a disk, 14.

Secured to the guide-tube at 15, Fig. III, is a wire or other spring, 16, which fits in a groove formed by a rib, 17, on one of the plates 13. The plate is cut out at the upper end of 65 the rib, as shown at 18, forming an opening, into which the outturned end 19 of the spring projects when the cap is in its lower position, thus securely holding the cap down upon the globe and holding the latter down upon the 70 burner.

When it is desired to lift the globe to expose the burner, it is only necessary to press with the finger against the end 19 of the spring, and then by lifting the plates (which are 75 grasped by the fingers in pressing the spring inward) the globe is raised, as stated, the part 19 of the spring moving in the groove formed by the rib 17.

At the lower end of the rib 17 there is preferably an enlargement, 20, as shown in Fig. III, to receive the end 19 of the spring, for the purpose of holding the globe in its elevated position, as shown in Fig. IV. By simply pressing down on the globe or on the plates 85 the part 19 of the spring leaves the enlargement in the rib automatically.

In addition to the rib 17 to receive the spring, or in lieu thereof, the guide-tube 8 may have a depression, 21, as shown in Fig. 90 VIII.

I claim as my invention—

1. In a lantern, in combination with the globe and perforated disk, the fasteners fitting in perforations in the disk and provided with 95 upper portions, 11, and under portions, 12, as set forth.

2. The combination, with a tubular lantern provided with a guide-tube, globe, and cap, of the plates secured to the cap, one of which is 100 provided with a perforation, and the spring secured to the guide-tube having an outturned

upper end entering said perforation in one of the plates, substantially as described.

3. The combination, with a tubular lantern provided with a guide-tube, globe, and cap, of the plates secured to the cap, one of which is provided with an enlargement, and the spring secured to the guide-tube having an outturned upper end entering said enlargement in one of the plates, substantially as described.

4. In a lantern, in combination with the air-tubes, guide-tube, globe, and cap, the plates secured to the cap on either side of the guide-tube, and a spring secured to the guide-tube at its lower end and provided with an out-turned end, 19, one of the plates having a rib

to form a groove for the outturned end of the spring, substantially as and for the purpose set forth.

5. In a lantern, in combination with the air-tubes, guide-tube, globe, and cap, the plates secured to the cap on either side of the guide-tube, and a spring secured at its lower end to the guide-tube and having a perforation, 19, one of the plates being formed with an opening, 18, a rib, 17, and an enlargement, 20, substantially as and for the purpose set forth.

FERDINAND MEYROSE.

In presence of—

GEO. H. KNIGHT,
JOSEPH WAHLE.
